Primary Examiner — Darlington Ly(74) *Attorney, Agent, or Firm* — Cantor Colburn LLP(57) **CLAIM**

We claim, the ornamental design for an element of a vehicle bumper system, as shown and described.

DESCRIPTION

FIG. 1 is a front perspective view of an element of a vehicle bumper system showing our new design;

FIG. 2 is a rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken lines in the drawings illustrate portions of an element of a vehicle bumper system that forms no part of the claimed design.
